UNITED STATES PATENT OFFICE.

HENRY J. TIBBENS, OF DANVILLE, ILLINOIS.

DEVICE FOR REPAIRING BOILER-FLUES.

1,004,310.

Specification of Letters Patent. Patented Sept. 26, 1911.

Application filed February 28, 1911. Serial No. 611,467.

To all whom it may concern:

Be it known that I, HENRY J. TIBBENS, citizen of the United States, residing at Danville, in the county of Vermilion and State of Illinois, have invented certain new and useful Improvements in Devices for Repairing Boiler-Flues, of which the following is a specification.

This invention relates to improvements in the means for repairing boiler flues, and has for one of its objects to provide a simply constructed device whereby broken or fractured ends of boiler flues may be repaired and without reducing the heating surface or weakening the structure of the tube or the flue sheet.

Another object of the invention is to provide a simply constructed device whereby the repaired flue is protected from the influence of excessive heat.

With these and other objects in view the invention consists in certain novel features of construction, as hereinafter shown and described and then specifically pointed out in the claim, and in the drawings illustrative of the preferred embodiment of the invention, Figure 1 is a longitudinal sectional view of a portion of a flue and portions of a flue sheet illustrating the manner of applying the improved repairing device; and Fig. 2 is a section on the line 2-2 of Fig. 1.

Corresponding and like parts are referred to in the following description and indicated in all the views of the accompanying drawings by the same reference characters.

The improved device may be applied without material structural change to boiler flues of different sizes and to boiler flues manufactured from different materials, but for the purpose of illustration is shown applied to the flue-sheet and a flue of a conventional generator, a portion of the flue sheet at the fire box end being represented conventionally at 10 and a portion of a flue at 12. It will be assumed that the flue 12 has been fractured at the fire-box end, the fractures generally taking place close to the flue sheet, and when this occurs a plurality of small apertures 13 are formed in the side of the flue near the ends, three of the apertures being generally formed, one at the bottom and one at each side, as shown.

The improved attachment comprises a thimble 14 corresponding in outer diameter to the inner diameter of the fractured flue and inserted into the flue, as shown in Fig. 1.

The thimble is provided at its outer end with an annular bead 15, which extends beyond the adjacent edge of the original flue, as shown. After the thimble has been inserted 60 into the flue the thimble is beaded, as shown at 16, to couple the thimble to the flue sheet, and another bead 17 formed in the thimble intermediate the bead 16 and the inner end of the thimble to couple the thimble to the 65 flue, the flue being likewise beaded or pressed outwardly in the form of an annular bulge or projection, as represented at 18. By this means the thimble 14 is coupled steam and water tight to the flue sheet and likewise 70 coupled steam and water tight to the flue, the "beading" being accomplished in the usual manner by implements provided for that purpose.

In producing the coupling bead 16 the 75 outer expansion of the material of the thimble likewise presses the material of the flue outwardly, as indicated in Fig. 1, thus leaving a space between the two beads that does not bear closely against the inner face of the 80 flue, thus leaving a slight space so that the water will freely circulate through the vent openings 13 between the thimble and the adjacent portion of the flue, thereby preventing unequal expansion and contraction which 85 would otherwise destroy the integrity of the joint formed by the beads. This is an important feature of applicant's device and materially increases its efficiency and utility, as thereby all danger of unequal expansion 90 and contraction is prevented.

The improved device is simple in construction, can be readily constructed to fit flues of various sizes and renders the flue 12 equally as strong as it was originally, hence 95 the repaired flue will last as long as the originally new flue. The improved device does not lessen the heating surface, while the vents 13 by permitting the free circulation of the water prevent the deterioration by 100 the intense heat to which devices of this character are subjected both from the inside and outside.

The vents 13 are preferably formed by cutting U-shaped clefts through the material of the flue and bending the tongues thus produced outwardly, as shown, thus avoiding the necessity for cutting out any of the metal. Any required number of the vents 110 may be employed, but generally three will be sufficient, as shown.

The improved repairing thimble renders

the repaired flue practically as good and as strong as the original flue, and does not as before stated, reduce the heating surface, which is the principal objection to the cast 5 iron plug usually employed for repairing broken flue ends.

Preferably the usual copper gasket or expansion ring 19 will be left in position as shown.

10 Having thus described the invention, what is claimed as new is:—

The combination with a boiler flue having vent openings near the end, of a thimble extending into said flue and beyond the vents

and with an outwardly directed bead at the 15 outer end adapted to engage against the flue sheet, said thimble being further beaded between the vent opening and the flue and also near its inner end whereby the flue material is pressed outwardly and spaced slightly 20 from the thimble to provide for circulation of water between the flue and thimble.

In testimony whereof, I affix my signature in presence of two witnesses.

HENRY J. TIBBENS. [L.S.]
